UNITED STATES PATENT OFFICE.

GEORG BÖTTICHER, OF WURZEN, SAXONY, GERMANY.

DESIGN FOR MOHAIR PLUSH.

SPECIFICATION forming part of Design No. 15,924, dated March 10, 1885.

Application filed September 17, 1884. Term of patent 3½ years.

To all whom it may concern:

Be it known that I, GEORG BÖTTICHER, of Wurzen, in the Kingdom of Saxony and Empire of Germany, have invented and produced 5 a new and original Design for Mohair Plush, of which the following is a full, clear, and exact description.

Reference is to be had to the accompanying drawing, forming a part of this specification, 10 and which fully illustrates my design.

The leading feature of my design consists in the representation of a stem bearing fanciful leaves A, blossoms B, and fruit C. The cluster of fruit of each stem is at the side of 15 and a little below the lower blossom of an adjacent stem on the same horizontal row with the first stem, and above the space between

the blossoms of a stem in the next lower row, so that the stems in adjacent rows will alternate, as shown in the accompanying drawing. 20

I claim—

The design for mohair plush herein shown and described, the same consisting of the representation of a stem bearing fanciful leaves, blossoms, and fruit, the fruit of each stem being at the side of and a little below the lower blossoms of an adjacent stem on the same horizontal row and above the space between the blossoms of a stem in the next lower row, as shown. 25

GEORG BÖTTICHER. [L. S.]
